SPEAKING CLOCK

Domingo Delgado, Habana, Cuba

Application April 9, 1946, Serial No. 660,833
In Cuba March 8, 1943

3 Claims. (Cl. 58—14)

1

This invention relates to the art of reproducing sound at pre-determined intervals under the control of a clock, and in its more specific aspects it relates to an apparatus of this character which is entirely automatic in operation.

It is an object of this invention to provide a sound reproducing mechanism in which the sound is carried on a film and electronically picked up therefrom for reproduction, the film also carries means for controlling certain circuits within the apparatus whereby the operation of the apparatus is regulated.

A further object of this invention resides in an apparatus of this character which is relatively inexpensive to operate and is automatic in operation requiring no attention except when a change of film is made to reproduce different sounds.

These and other objects, as will hereinafter appear, are accomplished by this invention which is described in the following specification and shown in the accompanying drawings.

Fig. 1 is a wiring diagram of the apparatus.

Fig. 2 is a schematic showing of the apparatus.

Fig. 3 is a plan view of a section of the film strip.

Fig. 4 is a view in side elevation of the film and showing certain of the switches controlled thereby.

In practicing my invention I use any desirable type of clock mechanism having the usual minute hand axle 1 for rotating the minute hand 1a of the clock. A cam wheel 2 is fixed on axle 1 for rotation therewith and is provided on its periphery with circumferentially spaced cam projections 2a. Within the clock I mount in any suitable manner a pivot pin 4 pivotally carrying a pawl 3 and an integral arm 3a. The pawl is mounted to project in position in the path of projections 2a while arm 3a extends at an angle relative to the pawl, the arm being provided with notches 52 and 53 on the under surface thereof. An upstanding lever 5 is mounted on a pivot pin 6 fixed within the clock, the lever 5 extending upwardly into notch 53. Lever 5 is provided with a projection 14 while arm 3a is provided with a similar projection 7.

An insulating block 9 carries two electrical contact members 8a and 8b extending therefrom, the member 8a being longer than member 8b and being flexible and in engagement with projection 7. Opposed contact points 8 and 8c are formed on members 8b and 8a. A similar insulating block 16 carries similar electric contact members 15 and 15a, the longer of which is in engagement with projection 14 on lever 5. Contact points 15b and 15c are provided on members 15a and 15.

2

The electric contact members 8a, 8b, 15 and 15a are connected into the electrical circuits of the apparatus at 10, 11, 17 and 18, respectively.

As cam 2 rotates the cam projections 2a will rock pawl 3 and arm 3a on pivot 4 releasing lever 5 from notch 53 whereupon it will move under the tension exerted by flexed contact member 15 into notch 52 whereupon contact points 15b and 15c will close. Likewise arm 3a will rock downwardly and contact points 8 and 8c will close.

An electro-magnet 48 which is connected into the electric circuits of the apparatus at 12 and 13 is disposed adjacent the lever 5 and upon excitation of the magnet the lever is attracted from position in notch 52 into notch 53 and contacts 15b and 15c are opened. The controlling means for the electro-magnet will be explained hereinafter. It will be apparent that when lever 5 is in notch 53 contacts 8 and 8c will be open.

Combined in the circuit is an electronical amplifier 19 and a loudspeaker 20. A photoelectric cell 21 sends the signal to the amplifier which it receives from film 24, the numeral 22 designating an exciter tube and 23 any suitable optical system. Thus the film 24 is scanned as it moves past the pick up device.

The film 24 is carried on reels 50 and 51, the movement of the film being produced by means of sprocket wheels 25 which are rotated by a reversible synchronic motor, the direction of rotation of the motor being controlled by a pair of double relays 31 and 33 in a manner to be hereinafter made clear. The operative connection between the motor and sprockets may be of any conventional type.

The film is formed with a slot or perforation 27 at one end thereof for stopping the motor 36 when the film end is reached. A further slot or perforation 30 is provided at a pre-determined position in the strip for controlling the operation of magnet 48 as will be explained, while a further slot or perforation 35 is formed in film at the other end for stopping the motor when that end of the film is reached.

When the electric contacts 8 and 8c are closed the motor 36 commences operating and the film strip moves. The amplifier 19 is in operation due to closing of contacts 15b and 15c and the film is scanned and the sound is reproduced. I provide three rollers 28, 31 and 33 which roll on the film as it passes. The rollers are mounted on arms 33a which pivotally extend from a supporting framework 28a. Each arm carries an upstanding pin 31a thereon. The supporting framework 28 carries 3 sets of electrical connecting strips designated in their entirety by the nu-

meral 34 and the set for roller 33 includes a lower strip 34b having a contact 34c thereon and an upper strip 34d having a contact 34a thereon. The set of strips for roller 31, includes a lower strip 31b having a contact 31c thereon and an upper strip 31d having a contact 31e thereon, while the set of strips for roller 28 includes a lower strip 28b having a contact 28c thereon and an upper strip 28d having a contact 28e thereon. The strips extend over arms 33a, there being one set over each arm, and the upper strip of each set extends over a pin 31a and is upwardly flexed thereby so that the upper and lower contacts are separated and the circuit controlled thereby is open.

As the film strip moves with the rollers in contact therewith one of the slots on the film will be under whichever roller is aligned therewith. When the roller falls in the slot the arm 33a and pin 31a will fall and the upper and lower contacts of a particular circuit will be closed and a certain operation performed. The particular circuits and controls and the entire operation of the apparatus will now be explained in detail.

Upon examination of Fig. 1 of the drawings, cam 2 is illustrated with its angular cam projections, the cam being fixed on axle 1, which as I have pointed out, is the minute hand axle of the clock, and hence, makes a complete turn at every hour in its rotation in the direction of the arrow. As the cam rotates the cam projections engage the pawl 3 which pivots upon the pin 4 to raise the arm 3a so that the lever 5 is released from notch 53. The lever swings inwardly into the notch 52 under the tension of the flexed electrical connecting strip 15, so that the electric contacts 15b and 15c come together and close the circuit which connects the amplifier 19 into the electric power supply line. As the cam continues to rotate the pawl 3 is left free and out of contact with the periphery of the cam so that the arm 3a may drop to close the contacts 8 and 8c which closes the circuit and puts the synchronous motor 36 into the electric power supply line. When these two operations of circuit closing have been completed, the motor 36 begins operating and drives the sprocket wheels 25 to cause the film strip to move, and to be scanned as it passes the electronic pick-up device, including the photoelectric cell. The sounds which are photographed on the film are picked up and the signals sent to the amplifier 19 which amplifies and reproduces the sounds by means of the loud-speaker 20. The film strip 24 continues to move at a uniform speed until one of the slots on the film, such as 30, passes under the roller 31. When this occurs the roller 31 drops down or lowers and closes the electric circuit by engagement of the electric contacts 31c and 34c. The closing of this circuit connects the electro-magnet 48 with direct current which is supplied by the dry rectifier 47. Since the electro-magnet 48 is excited the lever 5 is attracted thereto out of its position in notch 52 in arm 3a and into its confined position in notch 53, whereupon the electric circuit controlled by contacts 8 and 8c and 15b and 15c are all opened, whereupon the operation of the motor 36 will stop the amplifier 19 will be disconnected from the supply line and of course the film strip will stop. It is to be understood that the magnet will be deenergized after the motor stops running for the inertia of the moving film strip will cause it to travel sufficiently to move the slot 30 beyond roller 31 so that contacts 31c and 31e will be separated and the circuit to the magnet opened. The opera-

tion will be repeated just as soon as the next cam projection 3a has moved into position contacting and moving pawl 3.

When the film strip reaches its end a slot 35 will pass under the aligned roller 33, the roller lowering and closing its particular contact points 34a and 34c. The closing of this circuit will put one of the double relay coils 38 into the direct current line which supplies the dry rectifier 47, which will attract in the direction of the arrow the armatures of the relay and this will close the electric contacts 39, 41, 43 and 44 to thereby reverse the rotation of motor 36 which will cause the film strip to be rewound on empty spool or reel 50 (see Fig. 2). While the film strip is being rewound on one of the spools the electric circuits are closed by means of the electric contact 43 which keeps the circuit of the coil of double relay 37 closed until a slot 27 in the film 24 which is disposed thereon at the other end of the film strip is reached and is under an aligned roller 28, which will drop or lower and open the electric contacts 28c and 28e which are connected in series with contacts 43 of relay 37 to thereby disconnect that relay from the circuit. The armature of the relay will consequently return to its original position opening the anterior contacts and closing the contacts 40 and 42, that reverse the rotation of the motor 36 and stop the operation thereof by opening the electric circuits 39, 41, 43 and 44. This operation being complete all is then in readiness to repeat the entire operation when the cam again moves the pawl 3.

I claim:

1. In a mechanism of the class described, a continuous strip having a sound record thereon, means for propelling the strip, photo-electric means for picking up the sound recorded on the strip and electric amplifying means therefor, a clock mechanism operable to start the operation of the means for propelling the strip and to connect the photo-electric means and the amplifying means into the electric current supply line, a switch controlling the operation of the propelling means for said strip and a further switch controlling the operation of the photo-electric pick up means and amplifier and said clock mechanism including a cam and an element actuated thereby, said element operatively associated with each of said switches to control the operation of the propelling means and the photo-electric pick up means and amplifier.

2. In a mechanism of the class described, a continuous strip having a sound record thereon, means for propelling the strip, photo-electric means for picking up the sound recorded on the strip and electric amplifying means therefor, a clock mechanism operable to start the operation of the means for propelling the strip and to connect the photo-electric means and the amplifying means into the electric current supply line, a pair of switches, one controlling the electric circuit to said propelling means and the other controlling the electric circuit to said photo-electric means and said amplifier, a pivoted arm operably associated with said switch controlling the photo-electric and amplifier means, the arm in one position holding the switch open and in another position permitting the switch to close, and said clock mechanism including a cam and an element actuated thereby, said element in one position in engagement with the arm to releasably maintain the switch controlled thereby in open position and said element operable by the cam to release said arm to position closing the switch, and said element operatively associated with said

switch controlling the electric circuit to the strip propelling means to open and close said switch when the other switch is opened and closed, and means moving said arm to position engaged with and releasably maintained by the element in position opening the switch controlled by the arm.

3. In a mechanism as set forth in claim 2, wherein said means moving said arm to position engaged with and releasably maintained by the element is an electromagnet.
